UNITED STATES PATENT OFFICE.

FRANK J. ROWSE, OF PAWTUCKET, RHODE ISLAND.

COIN-CONTROLLED VENDING-MACHINE.

No. 831,189.

Specification of Letters Patent.

Patented Sept. 18, 1906.

Application filed October 28, 1905. Serial No. 284,868.

To all whom it may concern:

Be it known that I, FRANK J. ROWSE, a citizen of the United States, residing at Pawtucket, in the county of Providence and State of Rhode Island, have invented certain new and useful Improvements in Coin-Controlled Vending-Machines, of which the following is a specification, reference being had therein to the accompanying drawings.

10 Like reference-numerals indicate like parts.

Figure 1 is a view of my improved vending-machine as seen partly in top plan and partly in section on line v v of Fig. 2. Fig. 2 is a view of the same as seen partly in elevation and partly in section on line x x of Fig. 1. Fig. 3 is a view as seen partly in elevation and partly in section on line y y of Fig. 2. Fig. 4 is a view as seen partly in elevation and partly in section on line z z of Fig. 2. Fig. 5 is a side elevation of my said machine. Fig. 6 shows in side elevation the coin, coin-carrier, and rocking cam when the coin is engaged in position and also the driving-lever operated by said cam. Fig. 7 shows in side elevation the same parts as Fig. 6 at the time when the coin is released from the coin-carrier. Fig. 8 is a perspective view of the case and exterior portions of said machine.

30 My invention relates to the class of coin-controlled vending-machines; and it consists of the novel construction and combination of the several parts or elements as hereinafter described, and specifically set forth in the 35 claim.

The case inclosing the operative parts of the mechanism consists of the base 1, the front 2, the back and the two side pieces 3. It has a cover 4, secured by hinges 5 to the 40 upper end of the back piece. The cover 4 is fastened by means of a hasp 6 and padlock 7 or in any other suitable manner. A drawer 8 is provided at the bottom of the case and is secured by a lock 9. A side portion or plate 45 10 of the frame, which supports the operative mechanism, extends through the case and is flush with the side piece 3. The plate 10 has a coin-aperture 11 through it. The crank-shaft 12 is rotatably mounted in the 50 side plates 10 and 13 of the frame, and on the end of said shaft which projects out beyond the plate 10 a crank 14 is fastened, by which said shaft 12 may be rocked. The stop-pins 15 16 limit the extent of the movement of the 55 crank 14. The shaft 12 has a coin-carrier fastened thereon which has an oscillating

movement with the shaft 12 when the crank 14 is turned in the arc of a circle as limited by the stop-pins 15 and 16. This carrier consists of two side plates 17 17 and a front plate 18. 60 The front plate 18 has a vertical slot 19, as seen in Figs. 1, 2, 3, and 5. On each side plate 17 is a sleeve or tubular bearing 20, which is fastened by a rivet or set-screw on the shaft 12. A coin-chute 21 is fastened to 65 the top of the front plate 18 and an opening therein registers with the coin-aperture 11 of the plate 10. At the lower corners of the coin-chute 21 are the coin-rests 24 24 for the coin 23. A spring 25 is fastened at one end 70 to an eye or lug 22 in the upper portion of one of the side plates 17 and at its opposite end to the stud 26, which projects from the frame. This spring normally holds the coin-carrier in the position illustrated in Fig. 2 and keeps 75 the crank 14 in contact with the stop-pin 15 when the machine is not in operation. A coin-ejector 27 extends in a bracket form from the inner side of the plate 10 of the frame, as shown in Fig. 3, and is in alinement 80 with the slot 19 of the front plate 18 of the coin-carrier. Up to this point the coin mechanism is the same as that shown in Letters Patent of the United States No. 764,679, dated July 12, 1904, and issued to me for improvements in coin mechanism for vending-machines. 85

A tubular sleeve 28 surrounds the shaft 12 and turns with it, being held firmly thereon by means of the set-screw 29. A toe 30 extends from the sleeve or tube 28, as seen in Figs. 1 and 3. A rocking cam 31 has a tubular bearing 32, by which it is loosely mounted on the shaft 12. This cam 31 is a sector-shaped plate, having a flange 33, whose edge 95 is curved, as best shown in Fig. 3, to form a working or cam surface. The plate has a stop-pin 34 at its upper corner and a slot, as seen in Figs. 2 and 6. A toe 35 extends from the tubular bearing 32 of the rocking cam 31. 100

A rock-shaft 36 is loosely mounted in the frame, as shown at 37 37. A sleeve or hub 38 is fastened on the rock-shaft 36 by a set-screw 39, and a driving-lever 40 extends from the sleeve or hub 38. The driving-lever 40 105 has a pin 41 at its upper end, which normally is held in contact with the stop-pin 34 of the rocking cam 31 by force of the spring 42; said spring being fastened at one end to a lug 43 of the driving-lever 40 and at the opposite 110 end to a lug 44, extending from the frame. Another sleeve or hub 45 is fastened on the

rock-shaft 36 by the set-screw 46 and carries a detaining-lever 47, whose upper end is formed into a concave seat 48. (Best illustrated in Fig. 5.) A spring 49 is fastened at one end to the detaining-lever 47 and at the opposite end to the lug 50 from the frame. Two other sleeves or hubs 51 52 are fastened on the rock-shaft 36 by the set-screws 53 54. These sleeves or hubs 51 52 have the delivery-levers 55 56, which at their upper ends project outwardly, as shown at 57 58. At these bent ends 57 58 are flanges 59 60, extending at right angles and directed toward each other. At the upper ends of the delivery-levers 55 56 are the L-shaped inwardly-directed bends 61, 61^a, 62, and 62^a. Two brackets or shelves 63 64 are secured to the frame of the machine and extend inwardly, as shown in Figs. 1, 3, and 5. A magazine or chute 65 contains the articles which are to be delivered, those shown in the drawings being tubes 66, containing a towel 67, and they fit said magazine or chute 65 loosely and are adapted to drop therein by gravity. A piece of soap 68 is shown wrapped up in the towel 67.

25 The operation of my improved vending machine is as follows: The machine must be set up perpendicularly, as illustrated in Fig. 8, because the force of gravity is utilized in
30 the insertion and delivery of the rolls or packages 67 and in the insertion and ejection of the coin. Suppose the magazine 65 is supplied with a number of rolls or packages 66. These lie one upon another in a vertical pile
35 between the flanges of the magazine or chute 65, the lowest one of the series resting, as seen in Figs. 2 and 3, upon the top edges of the bent ends 61 and 62 of the delivery-levers 55 and 56. This is the inoperative position
40 of the machine, the crank 14 being held in contact with the stop-pin 15 by means of the spring 25. I will first explain the movement of the mechanism when there is no coin in position within the machine. An oscillation of
45 the crank 14 from the stop-pin 15 to the stop-pin 16 will under those conditions have no effect whatever upon the rocking cam 31, but will have its only effect upon the coin-carrier 17, which is fastened on the shaft 12, the toe
50 35 remaining in its normal position the meanwhile. When a coin 23 is inserted through the slot or coin-aperture 11, it enters the coin-chute 21 and slides by gravity down along the inclined plate 18 till it comes to the coin-
55 24 24, by which it is temporarily supported in position, as illustrated in Figs. 1 and 2. As the coin-carrier 17 is oscillated by the crank 14 in the direction indicated by the arrow 70 in Fig. 2, the sharp point of the toe
60 35 comes into forcible contact with the coin 23, and then the continuing movement of the coin-carrier 17 causes the coin 23 to press against and move the toe 35, and so imparts movement from the coin-carrier 17 to the
65 rocking cam 31, because said toe and rock-

ing cam are fastened together and both are loosely mounted on the shaft 12. As soon as the rocking cam 31 begins to oscillate on the shaft 12 in the direction indicated by the arrow 71 in Fig. 6 the stop-pin 34 clears the pin 41 of the driving-lever 40. The pin 41 by the movement of the rocking cam 31 is presently engaged by the curved cam edge of the flange 33 and is pressed downward by said cam edge. In this way the driving-lever 40 is moved, and so rocks the rock-shaft 36, to which the hub 38 of the driving-lever 40 is fastened. At the same time this oscillation of the rock-shaft 36 causes a like movement of the detaining-lever 47, whose hub 45 is fastened on said shaft. The detaining-lever 47 stands slightly in advance of the driving-lever 40, as seen in Figs. 3 and 5, and whereas in its normal position the detaining-lever 47 by its U-shaped slot (shown in Fig. 85 3) loosely receives the toe 30 through said slot said detaining-lever 47 by its oscillatory movement just described comes into the position illustrated in Fig. 5 and allows the toe 30 (which by the movement of the crank-shaft 12 has risen from the position shown in Fig. 3 to the position shown in Fig. 5) to be received into the concave seat of the detaining-lever 47, as seen in Fig. 5. During the continuance thereafter of the oscillation 90 of the rocking cam 31 said toe 30 is supported on the detaining-lever 47 in the concave seat 48 thereof, and although the detaining-lever 47 continues its oscillatory movement it engages slidingly the toe 30. Thus the engagement of the toe 30 with the seat 48 of the detaining-lever 47, so long as said engagement continues, prevents any return movement of the rocking cam 31 by the spring 25. At the same time the rocking of the shaft 36 100 causes the delivery-levers 55 56 (whose hubs 51 52 are fastened on the shaft 36) to move inwardly in the direction indicated by the arrows 72 in Figs. 3 and 5. During the time of this inward movement of the delivery-levers 110 55 56 the lowermost roll 66 is supported on the top edges of the bent ends 61 and 62, but when this inward movement of the delivery-levers 55 56 has proceeded till said levers are in the position indicated by dotted lines in Fig. 5 the lowermost roll 66, being no longer supported, falls by gravity into the position indicated by dotted lines 66^a. In this position the lowermost roll rests on the shelves 63 64, but is prevented from rolling off by the bent-forward ends 59 60 of the projections 57 58 of the delivery-levers 55 56. This displacement of the lowermost roll 66 from the position shown in solid lines in Fig. 5 to the position shown at 120 66^a in dotted lines in said figure causes the next higher roll in the chute 65 to descend by gravity to the position indicated in said figure by the dotted lines 66^b. In these movements of the several parts of the mechan- 125 130

ism above explained the springs have been put under increasing tension—namely, the spring 25 of the coin-carrier 17, the spring 42 of the driving-lever 40, and the spring 49 of the detaining-lever 47. These springs when released operate with considerable force. This release occurs when the tip end of the toe 30 is, by the oscillation of the rocking-cam 31, carried to the point where it no longer 5 is engaged in the seat 48 of the detaining-lever 47. Then the delivery-levers 55 56, the levers 40 and 47, the rocking cam 31, coin-carrier 17, and crank 14 all return to their normal positions. As in the normal 10 position the projections 57 58 of the delivery-levers 55 56 extend outwardly from the case and the roll 66^a is no longer supported by them, but has been swept off the shelves 63 64 by the portions 61^a 62^a of the delivery-levers 55 56, said roll is ejected forcibly by the springs and descends to the shelf 73, Fig. 8, where it can be taken by the purchaser, as shown at 66^c. In these return movements the pin 41 of the driving-lever 40 comes 15 again into contact with the stop-pin 34. When the crank 14 has come to the position shown in Fig. 7, the coin-carrier comes to the position shown in said figure, and the coin-ejector 27 then extends into the lower portion 20 of the slot 19 of the plate 18 of the coin-carrier 17. The coin-ejector 27 then comes into contact with the lower edge of the coin 23 between the two coin-rests 24 24. The continuing oscillatory movement of the coin-carrier causes said coin-ejector 27 (which is 25 stationary) to force upward the coin 23. Thus the coin 23 is dislodged from the coin-rests 24 24 and being no longer supported falls by gravity, as illustrated at 23^a, and so 30 falls into the drawer 8. In case a washer is deposited in the coin-chute 21 instead of a coin it descends and is seated on the coin-rests 24 24 and is pushed therefrom by the toe 35 just like a coin; but when the sharp 35 point of the toe 35 rises from the position shown in Fig. 2 to the position shown in Fig. 6 it passes freely through the hole of the washer and so the washer cannot press the toe 35 inwardly, and thereby move the rock- 40 ing cam 31. Consequently the machine does

not operate, and when the crank 14 returns to the pins 15 the washer, being then dislodged from the coin-rests 24 24 by the coin-ejector 27, drops into the drawer. So, too, when a pasteboard disk is inserted in the 55 coin-chute instead of a coin the second position of the toe 35 punctures the pasteboard disk, because it has not sufficient strength to move said toe and rocking cam as a coin has, and thus the machine remains inoperative 60 and the disk is cleared away by the coin-ejector 27 and drops into the drawer.

I claim as a novel and useful invention and desire to secure by Letters Patent—

In a machine of the class described, the 65 combination of a frame, two pivotally-mounted delivery-levers each having a forwardly-extending projection with an inwardly-directed bent flange, the distance between said projections being greater than the 70 length of the article to be vended and the distance between the inward ends of said flanges being less than the length of said article, said levers also each having a rearwardly-extending L-shaped projection the innermost ends 75 of which are distant from each other a space less than the length of said article, a magazine-chute supported by the frame and adapted to contain said articles and having an open bottom, a shelf on said frame and located beneath the open bottom of the chute, the said rearwardly-extending projections of the said delivery-levers being adapted to support the lowermost of the said articles in the chute when the machine is inoperative, 80 means adapted to give the delivery-levers an inward oscillation whereby said rearwardly-extending projections of the delivery-levers move out of contact with the lowermost of 85 said articles and allow said articles to drop to the shelf, and means adapted to give a forward oscillation to said delivery-levers whereby said article on the shelf is thrown from 90 said shelf.

In testimony whereof I affix my signature 95 in presence of two witnesses.

FRANK J. ROWSE.
